US00D779517S

(12) **United States Design Patent** (10) Patent No.: **US D779,517 S**
(45) Date of Patent: **** Feb. 21, 2017**

(54) **DISPLAY SCREEN OR PORTION THEREOF WITH GRAPHICAL USER INTERFACE**

(71) Applicant: **Shuttersong Incorporated**, Wellesley, MA (US)

(72) Inventors: **Paul Pierson**, New York, NY (US); **Kimiyo Nakatsui**, New York, NY (US); **Nick Spriggs**, New York, NY (US)

(73) Assignee: **Shuttersong Incorporated**, Wellesley, MA (US)

(**) Term: **14 Years**

(21) Appl. No.: **29/502,043**

(22) Filed: **Sep. 11, 2014**

(51) LOC (10) Cl. **14-04**

(52) U.S. Cl. **USPC .....** **D14/486**

(58) **Field of Classification Search**
